UNITED STATES PATENT OFFICE.

THEODORE J. RADKE, OF OAK PARK, ILLINOIS.

WATER-HEATER.

1,070,529.

Specification of Letters Patent. Patented Aug. 19, 1913.

Application filed April 22, 1909. Serial No. 491,449.

To all whom it may concern:

Be it known that I, THEODORE J. RADKE, a citizen of the United States, and a resident of Oak Park, in the county of Cook 5 and State of Illinois, have invented certain new and useful Improvements in Water-Heaters; and I do hereby declare that the following is a full, clear, and exact description thereof, reference being had to the accompanying drawings, and to the letters of 10 reference marked thereon, which form a part of this specification.

This invention relates to automatic water heaters for domestic and like uses wherein 15 the fuel, usually a gas, is automatically supplied to the burner upon the withdrawal of water from the heating receptacle and the admission of cold water thereto, the water being heated by the flame of the burner in 20 its passage through the receptacle and the fuel being automatically cut off when the withdrawal of water ceases.

The invention relates more particularly to 25 an improved safety device whereby the supply of fuel is cut off to the main burner and to the pilot burner in case of accidental extinguishment of the pilot burner flame so as to thereby avoid the waste of fuel and the attendant danger of fuel escaping into the 30 apartment containing the heater.

Among the objects of the invention is to provide a thermal device, which is under the control of the flame of the pilot burner, of an exceedingly simple, compact and efficient 35 construction, a construction which is very sensitive to the heat of the pilot burner flame so as to produce prompt operation of the safety device when the necessity occurs, and a construction which is strong and durable 40 so as to act effectively against the strong closing spring of the pilot burner valve.

Another object of the invention is to provide a connection between the thermostatic member of the safety device and the pilot 45 burner valve which is always in position to exert pressure against the closing spring of the pilot burner valve when the said member is under the influence of the heat of the pilot burner flame and thereby avoid possibility of a disconnection of the safety device either when the pilot burner is lighted or extinguished.

A further object of the invention is to provide an arrangement in heaters of this 55 kind wherein small quantities of hot water

may be withdrawn which is heated by the pilot burner alone and without lighting the main burner, thereby resulting in a material saving of fuel.

Other objects of the invention are to improve and simplify the construction and arrangement of the parts of the heater and to render the construction exceedingly compact and the operation thereof simple and efficient. 60

65 The invention consists in the matters hereinafter set forth and more particularly pointed out in the appended claims.

In the drawings, Figure 1 is a central vertical section of a heater embodying my invention. Fig. 2 is a cross section of the upper part of the jacket just below the cap, showing the coils and inlet and outlet pipes in plan view. Fig. 3 is a detail vertical section on line 3—3 of Fig. 1. Fig. 4 is a 70 horizontal section on line 4—4 of Fig. 1. Fig. 5 is a side elevation of one of the double helices constituting a section of the circulatory coil. Fig. 6 is a detail illustrating the manner of joining one of the coil sections to 75 a like coil section.

The casing or shell of the heater comprises a cast metal section 10, which is supported on the base 11, an upper jacket section 12 and a cap portion 13. The section 80 12 of the casing, when made to constitute a water jacket may comprise inner and outer thin sheet metal walls which incloses an annular water space 15. Contained within the lower section 10 of the casing is 85 a horizontal burner ring 17 which supports and is in communication with a plurality of upright burner tubes 18, 18 which may be made of any suitable or preferred construction. The burner ring is provided at 90 one side with an inlet nipple 20 which communicates with a gas supply pipe 21 through the medium of a conduit, designated as a whole by 22, which latter is made up of a number of suitably connected pipe 100 sections and valve fittings, as will herein-after more fully appear, arranged to control the supply of gas to the burners. The pipe 21 and conduit 22 are supported on a bracket 21' which extends laterally from 105 the lower cast section of the casing.

25 designates a cold water inlet or service pipe. It opens into a cylindric valve casting 26 that may be supported in any suitable manner on the casing of the heater. 110

- Said valve casing communicates, as herein shown, with the annular water space 15 of the heater casing through the medium of a pipe 27 which communicates with a port 28 at the lower side of said valve casing. A piston valve 29 is located within the casing 26 between the inlet or service pipe 25 and the port 28 and controls the supply of water to the circulatory system of heater. The piston valve is forced inwardly by the pressure of the water in pipe 25 when the pressure on the other side of the piston valve is reduced by the withdrawal of water from the outlet side of the circulatory system, and when said piston valve passes the port 28 water is free to flow from the service pipe 25 to the circulatory system as will hereinafter appear. A by-pass 31 connects the inner and outer ends of the cylindrical valve casing 26 so as to equalize the pressure on the opposite sides of the piston valve to allow the valve to open and close promptly. The conduit 22 is provided with a main valve 35, which controls the passage of gas to the main burners, and above said main valve with a pilot valve 36 which controls the supply of gas to the pilot burner, and is also arranged to cut off gas from both the pilot and main burners. The main valve 35 is provided with a ported partition, the port of which is controlled by a conical valve disk 38 provided with a stem 39 that extends outwardly through a stuffing box 40 of the valve casing. Said valve disk is held to its seat by a spring 41, interposed between the same and a screw-threaded plug 42 on the inner side of the valve casing. The said valve disk is opened against the action of the spring 41, by means of a vertically swinging lever 43 which is operatively connected with and is controlled by the water inlet valve. Said lever 43 is pivoted between its ends to a plug 44 that is screw threaded to the outer side of the pilot valve casing 36. The said lever carries at its lower end a screw threaded adjusting lug 45 having a rounded head which bears against the outer end of the stem 39 of the main burner valve disk 38. At its upper end said lever 43 carries a loosely fitting collar 47 that has screw-threaded connection with the outer end of the stem 30 of the piston valve 29. With this arrangement, when the water valve is opened the main burner gas valve is at the same time automatically opened to admit gas to the burners, and when the water valve closes the gas valve is closed by its spring 41. 50 designates a pilot burner located within the casing section 10, below the level of the heads of the main burners 18. The mixing tube 51 of said pilot burner is supplied with gas through a pipe 53 which enters the conduit 22 between the main and pilot

burner valves. Said pipe is provided with a throttle valve 54 to limit the flow of gas therethrough. The pilot valve casing is provided with a ported partition, the port of which is controlled by a conical valve disk 56 that is held against its seat by a spring 57 which is interposed between said disk and the screw threaded plug 44 before referred to. The said valve disk 56 is provided with a stem 60 which extends inwardly through a stuffing box at the inner side of the casing. Referring now to the means whereby the said pilot valve is maintained normally open to admit of a supply of gas to the pilot burner, and to the arrangement for automatically closing the pilot burner valve when the pilot burner is extinguished, said parts are constructed and operate as follows: 65 designates a horizontally arranged thermostatic bar located above the pilot burner. It may be made of brass or other expansive material. The said bar is fitted to and is supported at its inner end on a thrust bracket 66 that extends inwardly from the casing section 10. The outer end of said bar extends through an opening in said casing section, and engages at its outer end a vertically swinging lever 68 that is pivoted at its upper end to the adjacent bracket 21', the bar engaging said lever near its pivoted end. The said lever 68 extends downwardly along side the casing section 10 and engages near its lower end an inwardly extending lug 70 on a lever 71 arranged outside of and generally parallel with a lever 68. The lever 71 is pivoted at its lower end to an arm or bracket 72 extending laterally from the lower casing section, said lug 70 being located near the pivoted end of the lever 71. The lever 71 carries at its upper end a screw threaded contact stud 74 having at its outer end a rounded head which engages the inner end of the stem 60 of the pilot valve disk 56. The upper end of the lever 71 extends into a slotted portion of the supporting bracket 21' whereby it is guided in its swinging movement. The pivot bracket 72 of the lever 71 may be likewise slotted to engage and guide the lower end of the lever 68.

The compound system of levers described and the thermostatic member 65 are so arranged and adjusted that when the pilot light is burning and its flame is impinging against the thermostatic member, the pilot burner valve will be held open sufficiently to supply gas to the pilot burner, and also to supply gas through the main valve to the main burners. When no water is being drawn from the circulatory heating coil, the main burner valve will be closed and the only gas supplied will be through the pilot valve, regulated by the throttle valve 54 in the pipe 53. In the event of accident 130

dental extinguishment of the pilot light, the thermostatic member 65 will become cool and will contract to allow the spring 57 to close the pilot burner valve, and thereby avoid the wasteful and dangerous escape of gas at such time. Not only is gas prevented from escaping through the pilot burner, but gas is at such time shut off from the main burner valve in case such valve be opened by the opening of the water valve.

To light the pilot burner the pilot valve may be held open temporarily by pressure applied to the lever 71 and until the thermostat 65 becomes heated sufficiently to hold the pilot valve open. The arrangement described of the thermostat 65 and the compounded levers 68, 71, directly interposed between the thermostat and the pilot burner valve, provides for an ample movement of the valve to admit gas to the pilot burner with a slight expansion of the thermostat. Therefore the thermostat will take prompt control of the pilot valve when the pilot burner is first lighted so that it is necessary to manually hold the pilot valve open but a few seconds when lighting the pilot burner. Moreover the thermostatic action is applied directly to the valve so that the valve cannot close as long as the pilot burner is lighted.

Referring now to the arrangement of the circulatory coils, in which the water is heated as it passes therethrough and from which the hot water is drawn, the same is made as follows: The said coils are contained within the jacketed section 12 of the heater casing and, as herein shown, comprise a plurality of superposed sections, each consisting of two double helices 80. Each double helix consists of an upper member 81 and a lower member 82 as shown in Fig. 5. The two helical coils of each section are nested together with the turns of their coils alternating. The said superposed helices are connected at their sides by unions 84, as shown more clearly in Fig. 6. The said coils connected as described, are arranged symmetrically within the heater casing about a central vertical tube or pipe 86 that is supported at its lower end on a post or standard 87 rising from the base 11 of the casing, and connected to the pipe by a screw-threaded sleeve or junction fitting 88. The said pipe 86 is provided with a plurality of superposed sets of radial downwardly and outwardly inclined supporting arms 90 which are attached at their inner ends to collars 91 fixed to said pipe 86 and extend at their outer ends to points near the casing wall. The lower members 82 of the helical coil sections rest on and are supported by the said arms 90, while the upper sections 81 are supported from the lower sections by reason of their integral connection therewith. Each branch of the coil thus arranged is connected at its upper end to a cross pipe 93, which

latter is connected by a pipe 94 with the water space 15 of the section 12 of the heater casing. The point of connection of said pipe 94 with the cross pipe 93 constitutes the dividing point of a branched circulatory system, and from this point the water circulates downwardly through the two branches of the coils toward the burners. Said two branches of the coils communicate at their lower ends with terminal pipes 96, 97, said pipes leading from the opposite sides of the coils. The pipe 96 extends radially inwardly and thence upwardly along side the central coil supporting pipe 86 and terminates at its upper end in a horizontal draw off pipe 99 which leads to a faucet 100. The terminal pipe 97 extends downwardly and thence radially inwardly and thence upwardly along side the post or standard 87, and its upper end communicates with a radially arranged return bend, consisting of two generally horizontal members 101, 102. The terminal end of said return bend enters the sleeve or fitting 88 that connects the central coil supporting pipe 86 with its supporting standard 87, and communicates through said sleeve or fitting with the pipe 86. The pipe 86 is provided at its upper end with a fitting 103 having a lateral branch 104 that communicates with a draw off pipe 105 that is arranged generally parallel with the draw off pipe 99. Said pipes 105 and 99 have looped connection with the draw off faucet 100. It will thus be seen that water entering the divided coils from the pipe 94 passes downwardly through the separate coils, and that the water from one of the coils or branches passes upwardly through the terminal pipe 96 and draw off pipe 99 to the faucet 100, while water from the lower end of the other coil or branch passes through the terminal pipe 97, through the members 101, 102 of the return bend, the coil supporting pipe 86 and draw off pipe 105 to the faucet. Thus when water is being drawn from the faucet the flow of water divides at the point of connection of the pipes 94 and 93 and passes through the two branches of the coils to the faucet in parallel with said pipe 94 and faucet 100. With this arrangement I may make the coils of smaller cross section and thereby promote the rapid transmission of heat to the water, while avoiding resistance to the passage of water, such as would occur if water were passed through a pipe of like diameter and of a length equal to the combined lengths of the two branches. Instead of connecting the coils with the source of cold water supply through the water space 15 of the jacketed casing I may connect said coils directly with the pipe 27.

It will be observed by reference to Fig. 3 that the pilot burner head is provided with a central opening immediately beneath the

thermostatic member 65 and with two side openings arranged to direct flame against the members of the loop or return bend.

The provision of the divided or branched 5 circulatory coils within the heater casing, connected at one side with the service water pipe and at its other side with the draw off faucet, provides within the heater (when no water is being withdrawn therefrom) a 10 closed loop through which the water may circulate, and the arrangement of the pilot burner adjacent to the lower part of this loop provides means for maintaining a circulation of water in said loop and for keeping 15 the water which circulates through the loop heated. This arrangement is of great practical advantage inasmuch as the water at the faucet is always heated so that the first water drawn off from the faucet is hot 20 water. While the water is drawn off from the coils cold water enters the coils and said cold water is heated as it passes through the branches of the coils. There is therefore an uninterrupted 25 of the flow of hot water from the faucet from the time the faucet is opened to draw the water from the device until the faucet is closed after the withdrawal of all the water required. The branches of the coil are connected in parallel 30 with the cold water pipe and draw off device so that the flow of water through the heater, when water is being withdrawn, is divided in a manner to most advantageously apply the heat of the burner to the water to 35 heat the same. The arrangement is such, however, that when the draw off device is closed, the branches of the coil are connected in series, so that the branches constitute the closed loop referred to through which the 40 water is constantly circulating past the draw off device and the pilot burner and is maintained heated so as to provide heated water at the draw off device at all times.

The horizontally arranged deflector 108 45 is shown as supported on the coil supporting pipe 86 a distance above the bottom coils to deflect the flames outwardly over the inclined nest of coils and prevent them passing centrally upwardly through the casing 50 around the said pipe 86.

Means are provided for maintaining a substantially uniform temperature of water drawn from the device while the faucet is open for that purpose. Said means embraces a thermostatic member that is exposed to the heat of the outflowing hot water, and which is connected with and controls the supply of gas to the main burners. My improved arrangement for effecting this 55 result is made as follows: 110 designates a thermostatic bar, made preferably of zinc, that is contained within the hot water outflow pipe 86. It is seated at its lower end on the upper end of the standard 87 and 60 extends at its upper end through a stuffing

box in the fitting 103 at top of said pipe 86. The bar engages at its upper end the underside of a vertically swinging lever 112 which is pivoted at one end to a bracket 113 supported on said fitting 103. The lever 112 bears at its other end against the under side of a second lever 114 which is pivoted at one end to a bracket 115 supported on the fitting 103. Said latter lever extends at its other end outside the casing through an opening 70 in the cap member 13, and it is provided at its outer end with a vertical opening through which extends a rod or link 116. Said link extends downwardly along side the heater casing and carries at its lower end a valve disk 118, located within a valve casing 119, which constitutes part of the gas supply conduit 22. The said valve disk 118 is an upwardly closing disk and controls a port in a diaphragm or partition 120 in said 80 valve casing. The thermostatic bar 110 is so adjusted with respect to the compounded levers 112, 114 as to close the valve disk 118 against its seat upon the rising of the temperature of the outflowing hot water above 85 a predetermined point, while allowing the valve to remain open to permit gas to be supplied to the main burners up to the prescribed or normal temperature at which the water is intended to be delivered from the 90 heater. A spring 125, interposed between the upper side of the lever 114 and a nut 126 screw-threaded to the upper end of rod 116, provides means for regulating the closing movement of said regulating valve. By 95 proper adjustment of the thermostat in the hot water outlet pipe the valve controlled thereby may be arranged to open only after a predetermined reduction of temperature 100 of the outflowing water, somewhat below the temperature maintained in the coil by the pilot burner, so that small quantities of hot water may be withdrawn from the coil 105 without admitting gas to the main burners. Thus, when small quantities of water are 110 withdrawn at comparatively infrequent periods, the water may be heated entirely by the pilot burner and without lighting the main burner, thus resulting in a material saving of gas.

The cap piece 13 is provided at its top 115 with an opening 130 for the outlet of the products of combustion, over which a pipe is adapted to be set. In order to prevent cold air from falling downwardly through said opening upon the coils I provide the cap piece at its sides with a plurality of openings 131, and arrange between the outlet opening 130 and said side opening 131 a deflector plate 132 which deflects air falling 120 downwardly through the opening 130 to and through the radial or side openings 131.

The water space 15 is divided by a partition or partitions arranged to direct the water on its way from the pipe 27 to the 125 130

pipe 94 through restricted passages around the jacketed section 12. As herein shown a spiral passage is thus formed by a spirally arranged partition 135 which extends from 5 the bottom to the top of said water space.

The construction and arrangement of the circulatory tubes within the casing is not herein claimed, this being the subject of a separate application for United States Letters Patent, Serial Number 512,941, filed 10 August 16, 1909, a division of this application.

It will be understood that the structural details of the heater and its regulating devices may be varied within the spirit and scope of the invention and I do not limit the invention to the details herein shown, except as such details may be made the subject of specific claims.

20 I claim as my invention:—

1. In a water heater, the combination with a receptacle having means for connecting it with a source supplying cold water and with a draw off device, of a main burner, a 25 pilot burner, a conduit for supplying gas to the main burner, a main burner valve in said conduit having means to operate the same, a pilot burner valve in said conduit between the induction end thereof and the 30 main burner valve, a closing spring for said pilot burner valve, a pipe leading from the conduit at a point between said valves to the pilot burner, a short thermostatic bar over the pilot burner, a thrust member to 35 receive one end of the thermostatic bar, and means between the other end of the said bar and said pilot burner valve to transmit continuous variable thrust of said bar directly against the pilot burner valve spring to variably open said valve when the bar is heated by the pilot burner flame while permitting the pilot burner valve to close upon the extinguishment of said flame.

2. In a water heater of the character set 45 forth, the combination with the main and pilot burners, a conduit for supplying gas thereto, main and pilot burner valves in said conduit, with means to operate the main burner valve, a pipe leading from the conduit at a point between said valves to the pilot burner, a short thermostatic bar over the pilot burner, a thrust member adjacent to said conduit having a seat to receive one end of the said bar, and connecting means 50 between the said pilot burner valve and the other end of said bar to transmit continuous variable thrust of said bar directly against the pilot burner valve spring to variably open said valve when the said bar is heated by the pilot burner flame, while permitting the pilot burner valve to close upon the extinguishment of said flame.

3. In a water heater of the character set

forth, the combination with the main and pilot burners, with means for supplying gas 65 thereto, main and pilot burner valves, with means for operating the main burner valve, a thermostatic bar over the pilot burner having means to anchor it at one end; a lever pivoted at one end with the other end of said 70 bar bearing thereagainst near the pivot of said lever, a second lever pivoted at one end and bearing against the pilot burner valve at its other end, said first lever bearing against the second lever adjacent to the 75 pivot of the latter, and a closing spring applied to the pilot burner valve and acting against the thrust of said thermostatic bar.

4. In a water heater, the combination with a receptacle having means for connecting it 80 with a source supplying cold water and with a draw off device, of a main burner, a pilot burner, means for supplying gas to said burners, a main burner valve, pressure controlled means operated by the flow of water 85 through said receptacle for actuating said main burner valve, a pilot burner valve, a thermostatic bar over the pilot burner, a thrust member having a seat to receive one end of said bar, a closing spring for said 90 pilot burner valve, and connecting means between the said thermostatic bar and said pilot burner valve having means to transmit continuous variable pressure to said pilot burner valve against the action of its 95 closing spring.

5. In a water heater, a casing, a vertical pipe located centrally therein, water heating coils arranged in two branches, each branch comprising a series of superposed coil sections, supports carried by said central pipe upon which said coil sections are supported, a cold water supply pipe communicating with the upper ends of said branches, the lower end of one coil having an outflow terminal which extends upwardly through the casing and outwardly therefrom for connection with a faucet, and the terminal of the other branch communicating with the lower end of said central pipe, a draw-off 100 pipe communicating with the upper end of said central pipe and with said faucet, burners for heating said coil, a conduit for supplying gas to said burners, a regulating valve in said conduit, and a thermostatic 105 member in said central pipe operatively connected with said regulating valve.

In testimony that I claim the foregoing as my invention I affix my signature in the presence of two witnesses this 15th day of 120 April A. D. 1909.

THEODORE J. RADKE.
